E. T. CURRAN

LIQUID COOLING RADIATOR

Filed July 18, 1919

Inventor:
E.T. Curran
By his attorney
John O. Leifur

UNITED STATES PATENT OFFICE.

EDWARD T. CURRAN, OF DETROIT, MICHIGAN.

LIQUID-COOLING RADIATOR.

Application filed July 18, 1919. Serial No. 311,861.

To all whom it may concern:

Be it known that I, EDWARD T. CURRAN, a citizen of the United States, residing in Detroit, Wayne County, Michigan, have invented new and useful Improvements in Liquid-Cooling Radiators, of which the following is a specification.

This invention relates to liquid or water cooling radiators for use in connection with 10 internal combustion engines to cool the cooling medium for the cylinders of the engine and in which the liquid is cooled by conducting the liquid in passages with air spaces between the same from a tank or reservoir for 15 the heated liquid from the engine to a tank or reservoir for the cooled liquid and from which latter tank the liquid is delivered to the cooling jacket of the engine.

It is an object of the invention to arrange 20 the water conducting passages to present a large surface for the forcible impingement of the air against such tubes in its passage through the spaces between the tubes thereby greatly increasing the cooling efficiency 25 thereof, and to separate the reservoir for the heated liquid into compartments having communication with each other and with which compartments different portions of the tubes communicate, and arrange the inlet 30 to said reservoir so as to direct the incoming liquid to certain of the compartments and cause it to flow or circulate through the passages adjacent opposite sides of the radiator when the liquid is at a low temperature, comparatively speaking, and the partitions for 35 the compartments serving as spillways over which the liquid passes to the next adjacent compartment to flow through the passages connected to such compartments, by a rise in 40 temperature of the liquid and the consequent boiling and expansion of the liquid and thereby increasing the normal radiating surface for the liquid.

It is a further object of the invention to 45 provide in a radiator in which the liquid conducting and cooling passages comprise parallel and spaced vertical tubes of thin sheet material, means to be inserted in the spaces between the respective tubes to prevent un- 50 due expansion and the consequent rupturing or colpasing of the tubes, and so arrange such means as to direct the air passing through the spaces between the tubes in different directions toward the engine usually 55 located at the rear of the radiator to aid in the cooling of the engine by such air cur-

rents; and to arrange such means as to form obstructions and surfaces for the impingement and consequent agitation of the air in its passage through the spaces between the 60 passages.

A further object of the invention is to arrange the reservoir for the heated liquid with an enlarged or extended portion to serve as an expansion chamber or space for the 65 liquid thus obviating the necessity of an overflow outlet for any expansion of the liquid in the radiator.

In the drawing accompanying and forming a part of this specification, Figure 1 is 70 a perspective view, partly in section, looking at the front of a liquid cooling radiator illustrating an embodiment of my invention.

Figure 2 is a sectional side elevation taken substantially midway through Figure 1. 75

Figure 3 is a sectional plan view to show the arrangement of the liquid circulating passages.

Figure 4 is a perspective detail view to 80 show the arrangement of the means inserted in the spaces between the passages to prevent undue expansion of the passages and to direct the air currents to the rear of the radiator in a predetermined direction.

Figure 5 is a perspective view and Figure 85 6 an end elevation of a portion of the means shown in Figure 4 arranged with portions stamped therefrom to form obstructions to retard and agitate the air in its passage 90 through the radiator.

Similar characters of reference designate 95 like parts in the different views of the drawing.

The embodiment of my invention shown in the drawing comprises a reservoir or tank 7 having an inlet 8 for the liquid to be cooled, and a reservoir 9 for the cooled liquid having an outlet 10, said reservoirs being supported and connected in spaced relation by side members 11 to provide an open frame structure, and the side members provided with brackets 11' to secure the radiator to a support. The reservoir 7 has an opening in a tubular projection 12 closed by a removable cap 13. 100

The reservoirs 7 and 9 are connected in liquid circulation by a series of parallel and spaced flattened vertical tubes 14, preferably greater in cross sectional area from the front to the rear than the width. These tubes are arranged to extend from the front to the rear of the radiator at an obtuse angle to 110

the front of the radiator whereby a side surface of the tubes is presented for the impingement of the air in its passage through the spaces between the tubes, thus presenting 5 an enlarged surface for the air to forcibly strike against, it having been demonstrated that the force with which the air impacts or strikes against a heated body is an important factor in such air taking up and absorbing 10 heat radiated from such body. The tubes 14 are so arranged that the tubes at opposite sides of the center of the radiator incline inwardly or converge in a direction toward the center of the radiator, with one or more 15 of the tubes at the center extending substantially parallel to the side members 11, as shown in Figure 3, and thus obviating an enlarged space between the tubes at the center of the radiator. Experience has shown 20 that the liquid passing through the passages 14 adjacent the sides of the radiator will cool more quickly than the liquid passing through the tubes centrally of the radiator, and that the cooling efficiency of the 25 passages or tubes decreases the farther they are in from the sides with the passages or tubes in the middle of the radiator having the lowest cooling efficiency. Means are, therefore, provided to cause the initial flow 30 of the heated liquid to the outermost tubes. For this purpose dams or spillways 15, 16 are provided which are in the nature of partitions extending from the front to the back and from the bottom to adjacent the 35 top of the reservoir 7 separating said reservoir into a series of chambers 17, 17, 18, 18 and 18 having communication over the top of the partitions. To direct the incoming liquid to the chambers 17 a tubular member 40 26 is provided which extends along the lower rear portion of the reservoir and opens at opposite ends into the chambers 17 with the inlet 8 in communication with said member 26 at a point between its ends. By this 45 arrangement the incoming liquid is directed to the chambers 17 and circulates through the passages 14 in connection with said chambers to conduct the liquid to the reservoir 9. As the liquid heats up and begins to boil 50 due to a rise in temperature it will spill over the top of the partitions 15 to the chambers 18 and circulate through the passages 14 in communication with said chambers thereby 55 increasing the cooling or heat radiating surfaces of the radiator for the liquid. As the temperature of the liquid rises and begins to boil in the chambers 18 it will spill over the dams 15 into the central chambers 18 and circulate through the passages 14 in communication with said chambers thus further 60 increasing the circulating or cooling area or outflow of the liquid from the reservoir 7.

The tubes 14 are made of relatively thin and light material, and to prevent rupturing 65 and collapsing of the tubes by the expansion

thereof due to an increase in the temperature of the liquid passing therethrough or otherwise, means are provided to engage in the spaces between the tubes, said means being in the nature of a comparatively stiff but 70 somewhat flexible bridge or bridges 21 (Figure 4) comprising a strip of sheet material transversely corrugated or crimped. These bridge members are inserted in the spaces between the tubes with alternate bends of 75 the flutes of the corrugations engaging opposite tubes. It will be obvious that while the bends of the flutes will firmly engage the tubes they will yield slightly to accommodate themselves to the expansion and contraction of the material of the tubes. The 80 bends of the corrugations form passageways for the air through the spaces between the tubes and to cause the air currents to converge at the rear of the radiator. For this 85 purpose the corrugations at the middle portion of the strips extend at right angles to the front edge of the strip, while the corrugations adjacent the ends of the strip incline at an obtuse angle to the front end 90 of the strip, the corrugations adjacent the top of the strip inclining downward while those at the bottom of the strip incline upward. By this arrangement the air passing through the radiator is directed to the engine, usually located at the rear of the 95 radiator, and materially aiding in the cooling of the engine. Furthermore, inclining the tubes 14 at opposite sides of the center of the radiator as above set forth greatly facilitates the directing of the air against the engine. 100

As stated the force with which a current of air impacts or strikes against a heated object is an important factor in the air cooling of such object, and while the corrugated strips, to which the heat is transmitted from the tubes 14, present a large cooling surface to the air to further augment the cooling 105 efficiency of these corrugated strips portions are stamped and pressed therefrom, as shown at 23, to project into the air channels to form obstructions for the air to strike against, which also retard and cause the air to be agitated in its passage through the radiator. 110

To provide for expansion of the liquid in the radiator as the temperature rises, the reservoir 7 has a lateral extension 25 at the top, which is in the nature of an expansion chamber. It will be obvious that as expansion of the liquid takes place the increased volume will enter such space, and as contraction takes place by the cooling of the liquid it will readily run into the reservoir 7 due to the inclination of the lower wall or bottom of said extension. 115

In practice it has been found that with the liquid at a low temperature by the arrangement of the compartments 17 and 18 120

- in the reservoir 7 and the directing of the incoming liquid to the outer compartments 17 that the circulation of the liquid will be through said compartments, the 5 tubes 14 connected therewith and the reservoir 9, and to prevent freezing of any liquid in the tubes in communication with the compartments 18 in the use of the radiator in cold weather there are restricted outlets 10 through the wall of the member 26 into the chambers 18 to permit sufficient of the heated liquid to enter said chambers to heat the liquid therein and the connected tubes to prevent freezing.
- 15 Variations may be resorted to within the scope of my invention and portions may be used without others.
- Having thus described my invention, I claim:
- 20 1. In liquid cooling radiators, vertical tubes arranged in parallel and spaced relation, and corrugated members to engage in the spaces between the tubes with the corrugations arranged to cause the air currents passing through the spaces to converge in the rear of the radiator.
- 25 2. In a liquid cooling radiator, transversely extending and spaced tubes, and corrugated members to engage in the spaces between the tubes with the corrugations at the middle portion of the member extending at right angles to the front of the radiator, and the corrugations adjacent the ends extending at an obtuse angle to the front of the 30 radiator.
- 35 3. In liquid cooling radiators, vertical tubes arranged in parallel and spaced relation, and means to engage in the spaces between the tubes to reinforce the tubes and arranged to cause the air passing through said spaces to converge at the rear of the radiator.
- 40 4. In liquid cooling radiators, transverse tubes arranged in parallel and spaced relation, and corrugated members to engage in the spaces between the tubes, said tubes and the corrugated members being arranged to cause the air currents passing through the spaces between the tubes to converge in the 45 rear of the radiator.
- 50 5. In liquid cooling radiators, a series of parallel and spaced vertical tubes, and corrugated members to engage in the spaces between the tubes, the corrugations at the middle portion of said members being at right angles to the front of the radiator, with the corrugations adjacent the top inclining downward and inward from the front to the rear of the radiator and the corrugations 55 adjacent the lower end inclining upward and inward from the front to the rear of the radiator for the purpose specified.
- 60 6. In liquid cooling radiators, a series of parallel and spaced vertical flattened tubes arranged with a flattened side to extend at an obtuse angle to the front of the radiator, and corrugated members to engage in the spaces between the tubes with the corrugations arranged to cause the air passing through the spaces to converge in the rear of the 65 radiator.
- 70 7. In liquid cooling radiators, a series of parallel and spaced vertical flattened tubes, with the tubes arranged at one side of the center of the radiator to incline at an obtuse angle from the front to the rear of the radiator, and the tubes at the opposite side of the center of the radiator inclining at the same angle but in an opposite direction; and corrugated members to engage in the spaces between the tubes, the corrugations at the middle of said members being at right angles to the front of the radiator with the corrugations adjacent the top inclining downward and inward from the front to the rear of the radiator and the corrugations adjacent the lower end inclining upward and inward from the front to the rear of the radiator for the purpose specified.
- 75 8. In liquid cooling radiators, a reservoir for the heated liquid having an inlet; a reservoir for the cooled liquid; flattened tubes in parallel and spaced relation to conduct the liquid from one reservoir to the other and arranged at an angle to the front of the radiator to present a flattened side of said tubes for the impingement of the air in its passage through the spaces between the tubes; partitions in the reservoir for the heated liquid to separate said reservoir into chambers having communication with each other over the top of said partitions, and the inlet to said reservoir arranged to direct the incoming liquid to the two outermost chambers for the purpose specified.
- 80 9. In liquid cooling radiators reservoirs for the heated and cooled liquid; flat parallel and spaced liquid passages to connect said reservoirs in circulation; and transversely corrugated members interposed between said passages to form air passages between the liquid passages from the front to the rear of the radiators with the corrugations arranged to cause the air to converge in the rear of the radiator, said corrugated members having portions stamped therefrom to form perforations in the corrugated members.
- 85 10. In a radiator a core composed of flat parallel spaced tubes, and spacers for said tubes composed of transversely corrugated plates, said corrugations being arranged to incline downwardly and upwardly from the front to the rear of the core for the purpose specified.

EDWARD T. CURRAN.
